2 SHEETS—SHEET 2.

UNITED STATES PATENT OFFICE.

CHARLES H. NAPIER, OF MACON, GEORGIA.

CATAPULT.

1,374,757.

Specification of Letters Patent. Patented Apr. 12, 1921.

Application filed April 16, 1920. Serial No. 374,452.

To all whom it may concern:

Be it known that I, CHARLES H. NAPIER, a citizen of the United States of America, and a resident of Macon, county of Bibb, 5 and State of Georgia, have invented certain new and useful Improvements in Catapults, of which the following is a specification.

This invention relates to that class of devices used for throwing missiles, which are 10 generally termed catapults.

The main objects of the invention are to provide a catapult having improved means for effecting and directing the projection of a missile; to provide an improved form of 15 mounting for said means; to provide an improved construction and arrangement of mechanism on said mounting for setting said projecting means; and to provide a device of this kind which is particularly suitable for use in throwing clay pigeon targets.

An illustrative embodiment of this invention is shown in the accompanying drawings, in which—

Figure 1 is a perspective view of a catapult constructed in accordance with this invention.

Fig. 2 is a side elevation of the same.

Fig. 3 is a sectional elevation taken on the line 3—3 of Fig. 2.

Fig. 4 is a sectional elevation taken on the line 4—4 of Fig. 2.

In the specific embodiment herein illustrated the catapult comprises a mounting A, projecting means B, setting mechanism C, 35 and tripping or releasing mechanism D, so arranged that when set up in the desired location the apparatus may be manually or mechanically operated for successively setting the projecting means and after the 40 placing of a missile thereon, releasing the same for throwing the missile at practically any desired angle. The device represented in the drawings and more fully hereinafter described is one that has been constructed 45 particularly for use in throwing clay pigeon targets of the kind used in gun practice. It will be understood, however, that other forms of discharging means may be used when required to project missiles of different forms.

The mounting A herein illustrated comprises a base 1, a turret 2 and an idler bracket 3.

The base 1 is herein shown in the form of 55 a metal casting which is adapted to be se-

cured to a plank or other foundation member 4, by which the device is the more firmly mounted in the desired location.

The turret 2 is in the form of a plate 5 which is rotatably supported upon the base 60 1 by having a hub 6 seated in a socket 7 formed in said base and having upstanding arms or standards 8 upon which the projecting means and setting mechanism are supported. A lug 9 depending from the 65 forward edge of the turret plate 5 coacts with the lugs 10 (see Fig. 1) on the base 1 for limiting the rotational movement of the turret. Suitable adjusting screws 10^a are arranged on the lugs 10 for the purpose of 70 obtaining a closer adjustment of the angular movement of the turret 2.

The idler bracket 3 which carries the idler 75 11 constituting a part of the setting mechanism C, is herein shown in the form of a casting rigidly secured to the base 1 rearwardly of the turret and grooved to provide a guideway for the bar 12 which also forms a part of the setting mechanism C. Arms 13 of the bracket 3 extend upwardly and 80 forwardly over the turret so as to locate the idler 11 in proper position with respect to the axis of the turret 2, as will be more fully hereinafter explained.

The projecting mechanism B is similar in 85 construction to that described and claimed in my co-pending application Ser. No. 356,763, filed Feb. 6, 1920, and comprises a V-shaped frame 14 which is pivoted at its crotch to the standards 8 of the turret 2, 90 and has a platform 15 subtending the angle formed by said V-shaped frame, upon which a projecting member 16 is reciprocatingly mounted under the action of suitable power means 26 for coacting with said platform in 95 projecting missiles of the desired type.

The V-shaped frame 14 is pivotally supported in place by a pivot pin 17 secured to the upper ends of the standards 8 and has a depending arm 18 which is provided with 100 a slot 19 arranged concentrically with the axis of the pivot pin 17 through which a suitable clamping bolt 20 extends, whereby the angularity of the projecting means B with respect to the horizontal may be varied. 105

The platform or plate 15 and the projecting member 16 are of the type shown in the aforesaid patent. The platform 15 is secured at its ends to the ends of the V-shaped frame 14 and is provided with a guideway 110

21 extending throughout or a greater portion of the length thereof, along which the projecting member 16 is movable. A guide rail or flange 22 is arranged along one side 5 of the platform substantially parallel to the guideway 21 and supports a strip of friction material 23, preferably rubber, spaced above the platform 15 and extending inwardly toward the guideway 21, which strip coacts 10 with the projecting member 16 in guiding the missile and giving it the desired movement as it is discharged from the platform.

The projecting member 16 as herein shown is in the form of a block having suitable rollers 24 (see Fig. 2) secured to the sides thereof and received in suitable grooves or runways formed in the platform 15 at the sides of the guideway 21. A roller 25 is journaled on said block a predetermined distance above the face of the platform so as to properly engage the missile. The periphery of this roller preferably has a band of friction material such as rubber secured thereto which coacts with the rubber strip 23 during the travel of the missile along the platform to give it the desired action as it leaves said platform.

The power means 26 as herein shown is in the form of a comparatively heavy coiled 30 spring secured by a suitable swivel connection 27 near the upper end of one arm of the V-shaped frame 14, and at the other end to a chain 28 which runs over a roller 28^a on the frame 14 and is attached to an arm 29 35 on the pulley 30 forming a part of the setting mechanism, which will be more fully hereinafter described. The action of the spring 26 is transferred to the projecting member 16 through the medium of an arm 40 31 rigidly secured at one end to the pulley 30 so as to rotate therewith, and a link 32 connected at one end to the upper end of the arm 31 and at 33 to the projecting member 16.

45 A suitable locking pawl 34 is pivoted at 35 adjacent the rear end of the guideway 21 and normally urged by a spring 36 so that a shoulder 37 on said pawl is adapted to engage a shoulder 38 on the projecting member 16 and hold said projecting member in its set or retracted position.

The setting mechanism C comprises the pulley 30, idler 11 and bar 12, together with a flexible connection 39 secured at one end to 55 the bar 12 and passing around the idler 11 and over the pulley 30 and secured at its other end to a flat spring 40, these parts being so arranged that the pulling of the bar 12 outwardly rotates the pulley 30 against 60 the action of the spring 26 and through the medium of the arm 31 and link 32 shifts the projecting member 16 to the rear end of the guideway 21.

The pulley 30 is of the flanged type and 65 is journaled on the pivot pin 17. Lugs or

arms 41 extend radially outward from one point on the flanges of the pulley, which lugs are connected by a transverse bar or pin 42. These lugs 41 and pin 42 are so arranged that a knob 43 secured to the flexible 70 connection 39 is adapted to abut against the same when the bar 12 is pulled outwardly so as to cause the rotation of the pulley 30. By such an arrangement the flexible connection 39 is always available when it is desired to rotate the pulley 30 against the action of the power means 26, but is free to be shifted relatively of the pulley 30 under the action of the spring 40 independently of said pulley. Accordingly, the spring 40 80 normally urges the bar 12 toward the inner limit of its movement so that the inclined cam surface 44 thereon is brought into position to coact with the post 45 which forms a part of the tripping mechanism D, as will 85 more fully hereinafter appear.

The idler 11 and pulley 30 are of such diameters and their pivots relatively located so that that part of the flexible connection 39 leading from the periphery of one to the 90 other of said idler and pulley is disposed substantially in vertical alignment with the axis of the turret 2, so that regardless of the angular position of the turret 2 on the base 1 the setting mechanism C may be actuated by 95 the bar 12.

The flexible connection 39 is herein illustrated as a chain although it will be understood that a cable or rope may be used with equal effectiveness. 100

The bar 12, as has already been explained, is slidably supported on the idler bracket 3, the same being held in place by means of a pair of plates 46 attached to the top of the idler bracket 3 and overhanging the guideway in which said bar is slid able. This bar may be slid back and forth either manually or mechanically.

The tripping or releasing mechanism D comprises the post 45, a lever 47 and the bar 110 12. The post 45 is supported with its lower end in a socket 48 formed in the turret plate 5 concentrically with the axis of said turret. A spring 49 is located in the socket 48 and extends into a socket 50 formed in the end 115 of the post 45. This spring provides a resilient seat for said post, whereby said post may be vertically shifted. The lower portion of the post is properly shaped and recessed as at 51 so as to embrace that part 120 of the flexible connection 39 which extends from the periphery of the idler 11 and pulley 30, whereby said post is located in vertical alignment with the axis of the turret 2 so that its functional relationship to the 125 various parts of the mechanism remains constant regardless of the angular position of the turret 2.

The lever 47 is pivotally mounted at 52 on the frame 14 and has the end 53 thereof 130

bearing against the locking pawl 34 and the end 54 extending through a slot 55 formed in the upper end of the post 45. The slot 55 is shaped to provide knife-like edges 56 which bear against the lever 47 and constitute a shifting pivotal connection between the lever 47 and post 45, which is necessitated in order to avoid any binding of the parts of this tripping mechanism D when 10 the projecting mechanism B is shifted to various angular positions in a horizontal plane by the rotation of the turret 2 on the base 1, or has its vertical position varied through the tilting of the V-shaped frame 15 14 on the standards 8.

The bar 12 is provided with an inclined shoulder or cam surface 44 at its inner end and is adapted to coact with a shoulder 57 constituting the bottom of the recess 51 so 20 that an inward movement of the bar 12 will cause said cam surface 44 and shoulder 57 to coact to depress the post 45 against the action of the spring 49, thereby resulting in a shifting of the lever 47 so as to retract 25 the locking pawl 34 and disengage the shoulders 37 and 38.

The operation of the device herein shown is substantially as follows:

When it is desired to set the mechanism 30 for projecting a missile, the bar 12 is moved outwardly, which causes the flexible connection 39 through the abutting of the knob 43 on the lugs 41 to rotate the pulley 30 against the action of the spring 26, thereby causing 35 the arm 31 and link 32 to shift the projecting member 16 rearwardly along the guideway 21 until the shoulders 38 and 37 come into interlocking engagement. A missile, as for example a clay pigeon target 58, (see 40 Fig. 1) is placed upon the platform 15 in engagement with the friction strip 23 and the roller 25. As soon as a pull on the bar 12 is ceased the spring 40 shifts the chain 39 over the pulley 30 and draws the bar 12 45 back to the position shown in Fig. 2. The turret 2 and the projecting mechanism mounted thereon is shifted about vertical axis to the desired angular position and at the desired time or signal the bar 12 is 50 pushed inwardly so as to cause the inclined cam surface 44 to engage the shoulder 57 on the post 45 so that the post is depressed against the action of the spring 49. This 55 swings the lever 47 so as to cause the end 53 thereof to shift the locking pawl 34 in such a way as to disengage the shoulder 37 from the shoulder 38, whereupon the spring 26 acting through the pulley 30, arm 31 and link 32 shoots the projecting member 16 outwardly along the guideway 21 resulting in 60 the missile 58 being projected from the device. By reason of the momentum of the parts thus suddenly released the pulley 30 and arm 31 tend to move beyond their normal 65 positions as shown in Fig. 2. This

tendency is yieldingly checked by the spring 26 as the chain 28 is pulled around the roller 28 through this swinging of the arm beyond its aforesaid normal position prior to resetting. 70

Although but one specific embodiment of this invention has been herein shown and described, it will be understood that numerous details of the construction shown may be altered or omitted without departing from the spirit of this invention as defined by the following claims. 75

I claim:

1. A device of the class described, comprising a base, a member mounted thereon and adapted to direct the projection of a missile, means movable along said member for projecting the missile, an element rockably mounted on said base and connected to said projecting means, power means connected to rock said element for actuating said projecting means, mechanism connected to said element so as to rock the same against the action of said power means for setting said projecting means, a lock for holding 80 said projecting means in its set or retracted position, and means for retracting said lock so as to effect the release of said projecting means. 85

2. A device of the class described, comprising a base, a member mounted thereon and adapted to direct the projection of a missile, means movable along said member for projecting the missile, a pulley journaled on said base, an arm rigidly secured to rotate with said pulley and connected to said projecting means, power means connected to rotate said pulley for actuating said projecting means, a member shiftably mounted on said base, a flexible connection leading 95 from said shiftable member over said pulley and connected thereto whereby the shifting of said member will rotate said pulley against the action of said power means so as to shift said projecting means into its retracted position, a lock for holding said projecting means in its set or retracted position, 100 and means for retracting said lock so as to effect the release of said projecting means. 105

3. A device of the class described, comprising a base, a member mounted thereon and adapted to direct the projection of a missile, means movable along said member for projecting the missile, a pulley journaled on said base, an arm rigidly secured 110 to rotate with said pulley and connected to said projecting means, power means connected to rotate said pulley for actuating said projecting means, a member shiftably mounted on said base, a flexible connection 115 leading from said shiftable member over said pulley and having its other end connected to yielding means which normally urges said shiftable member toward one limit of its movement independently of the posi- 120

tion of said pulley, coacting abutting parts on said connection and said pulley whereby said shiftable member may be actuated to rotate said pulley against the action of said power means for the purpose of setting said projecting means, a lock for holding said projecting means in its set or retracted position, and other means for retracting said lock so as to effect the release of said projecting means.

4. A device of the class described, comprising a base, a member mounted thereon and adapted to direct the projection of a missile, means movable along said member for projecting the missile, a flanged pulley rotatably journaled on said base and having a lug extending radially outward from each of the flanges of said pulley and connected together at their outer ends, an arm rigidly secured to rotate with said pulley and connected to said projecting means, power means connected to rotate said pulley for actuating said projecting means, a bar shiftably mounted on said base, a chain connected 25 at one end to said bar and extending around said pulley and connected at its other end to yielding means supported on said base, a knob secured to said chain so as to abut against said pulley lugs whereby the shifting 30 of said bar in one direction rotates said pulley against the action of said power means for the purpose of setting said projecting member, said yielding means normally urging said bar in the opposite direction independently of the position of said pulley, a lock for holding said projecting means in its set or retracted position, and means for retracting said lock so as to effect the release of said projecting means.

40 5. A device of the class described, comprising a base, a turret rotatably mounted on said base and having a standard formed thereon, a member supported on said standard and adapted to direct the projection of a missile, means movable along said standard for projecting the missile, an element rockably mounted on said standard and connected to said projecting means, power means connected to rock said element for the purpose of actuating said projecting means, mechanism shiftably mounted on said base and connected to rock said element against the action of said power means for setting said projecting means, a lock for holding said 45 projecting means in its set or retracted position, and other means for retracting said lock so as to effect the release of said projecting means.

60 6. A device of the class described, comprising a base, a turret rotatably supported on said base and having a standard formed thereon, a member supported on said standard and adapted to direct the projection of a missile, means movable along 65 said member for projecting the missile, a

pulley journaled on said standard, an arm rigidly secured to rotate with said pulley and connected to said projecting means, power means connected to rotate said pulley for the purpose of actuating said projecting means, a bar slidably mounted on said base radially of the axis of said turret, an idler journaled on said base between said pulley and said bar, a flexible connection secured at one end to said bar and extending 70 around said idler and over said pulley, means on said flexible connection adapted to coact with said pulley whereby the shifting of said bar will cause the rotation of said pulley against the action of said power means for the purpose of setting said projecting means, said pulley and idler being of such diameters and journaled relative to each other so that the flexible connection leading from the periphery of one to the 80 other is disposed substantially in vertical alinement with the axis of said turret, a lock for holding said projecting means in its set or retracted position, and other means for retracting said lock so as to effect the release of said projecting means.

7. A device of the class described, comprising a base, a member supported thereon and adapted to direct the projection of a missile, means movable along said member for projecting the missile, power means connected to said projecting means for actuating the same, mechanism for setting said projecting means, a lock for holding said projecting means in its set or retracted 95 position, a post supported with its lower end in a socket formed on said base, the end of said post resting upon resilient means located in said socket, a cam member shiftable into and out of position to coact with 100 a cam surface on said post, whereby said post is adapted to be shifted against the action of said resilient means, and a connection between said post and said lock whereby the shifting of said post retracts 105 said lock so as to effect the release of said projecting means.

8. A device of the class described, comprising a base, a turret rotatably mounted thereon, a member mounted on said turret and adapted to direct the projection of a missile, means movable along said member for projecting the missile, an element rockably mounted on said turret and connected to said projecting means, power means connected to rock said element for actuating said projecting means, mechanism for shifting said element against the action of said power means for setting said projecting means, a lock for holding said projecting means in its set or retracted position, a post supported with its lower end in a socket formed in said turret concentric with the axis thereof, the lower end of said post resting 115 on resilient means located in said socket, 120 125 130

- 5 a cam member adapted to be shifted into and out of position for coacting with a cam surface on said post whereby the same is adapted to be depressed against the action 10 of said resilient means, and a connection between said post and said lock whereby the depression of said post retracts said lock so as to effect the release of said projecting means.
- 10 9. A device of the class described, comprising a base, a turret rotatably mounted thereon, a member mounted on said turret and adapted to direct the projection of a missile, means movable along said member 15 for projecting the missile, an element rockably mounted on said turret and connected to said projecting means, power means connected to rock said element for actuating said projecting means, mechanism for shifting said element against the action of said power means for setting said projecting means, a lock for holding said projecting means in its set or retracted position, a post supported with its lower end in a socket 20 formed in said turret concentric with the axis thereof, the lower end of said post resting on resilient means located in said socket, a cam member adapted to be shifted into and out of position for coacting with a 25 cam surface on said post whereby the same is adapted to be depressed against the action of said resilient means, and a lever pivoted on said member and having one end thereof connected to said post and the other contacting with said lock, whereby the depression of said post retracts said lock so as to effect the release of said projecting means.
- 10 10. A device of the class described, comprising a base, a turret rotatably supported 40 on said base and having a standard formed thereon, a member supported on said standard and adapted to direct the projection of a missile, means movable along said member for projecting the missile, a pulley journaled 45 on said standard, an arm rigidly secured to rotate with said pulley and connected to said projecting means, power means connected to rotate said pulley for the purpose of actuating said projecting means, a bar 50 slidably mounted on said base radially of the axis of said turret, an idler journaled on said base between said pulley and said bar, a flexible connection secured at one end to said bar and extending around said idler 55 and over said pulley, means on said flexible connection adapted to coact with said pulley whereby the shifting of said bar will cause the rotation of said pulley against the action of said power means for the purpose of setting said projecting means, said pulley and idler being of such diameters and journaled relative to each other so that the flexible connection leading from the periphery of one to the other is disposed substantially in 60 vertical alinement with the axis of said turret, a lock for holding said projecting means in its set or retracted position, a vertically disposed post supported with its lower end in a socket formed in said turret concentric with the axis thereof, the lower end of said post resting upon resilient means located in said socket, said post having the lower portion thereof recessed to embrace that portion of the flexible connection extending between said pulley and idler, said bar having an 65 inclined shoulder formed on the inner end thereof adapted to coact with said post at the lower end of said recess whereby the sliding of said bar inwardly will depress said post against the action of said resilient means, and a connection between the upper end of said post and said lock whereby the depression of said post will retract said lock so as to effect the release of said projecting means.

12. A device of the class described, comprising a base, a turret rotatably mounted thereon and having a standard integral therewith, a V-shaped frame pivotally mounted on said standard at the angle of said V, a platform subtending the angle of said V-shaped frame and adapted to direct the projection of a missile, means for adjusting the angularity of said platform with respect to said base, a member shiftably mounted on said platform and adapted to project the missile along said platform, a rotatable element journaled on said standard on an axis coincident with the axis of the pivot of said V-shaped frame, an arm secured to rotate with said element and connected to said projecting member, a spring secured at one end to said frame and at the other end to said rotatable element, whereby it is adapted to rotate said element so as to actuate said projecting member, mechanism arranged on said base and adapted to rotate said element against the action of said spring for shifting said projecting member into its retracted position, a lock on said frame adapted to hold said projecting member in its set or retracted position, and means also mounted on said base and adapted to be actuated for retracting said lock so as to effect the release of said projecting member.
13. A device of the class described, comprising a base, a turret rotatably mounted thereon and having a standard integral therewith, a V-shaped frame pivotally mounted on said standard at the angle of said V, a platform subtending the angle of said V-shaped frame and adapted to direct the projection of a missile, means for adjusting the angularity of said platform with respect to said base, a member shiftably mounted on said platform and adapted to project the missile along said platform, a pulley journaled on said standard on an axis coincident with the axis of said V-shaped member, an arm rigidly secured to said pulley to rotate therewith and connected to said projecting member, a spring secured at one end to one branch of said V-shaped frame and at the other end to said pulley and adapted to rotate said pulley for actuating said projecting member, a bar slidably mounted on said base in radial alinement with the axis of said turret, a flexible connection leading from said bar to and around said pulley, means on said pulley and said connection whereby said bar may be shifted so as to rotate said pulley against the action of said spring and shift said projecting member into its retracted position, a lock on said platform adapted to hold said projecting member in its retracted position, a post supported with its lower end in a socket formed on said turret concentric with the axis thereof, the lower end of said post resting upon a spring located in said socket, co-acting cam surfaces on said bar and post whereby said bar may be shifted to depress said post against the action of said spring, and a connection between the upper end of said post and said lock whereby the depression of said post will retract said lock so as to effect the release of said projecting member.
- Signed at Chicago this 13th day of April, 75
1920.

CHARLES H. NAPIER.
